Primary Examiner — Marianne Pandozzi*Assistant Examiner* — Jae Liang(74) *Attorney, Agent, or Firm* — Maschoff Brennan(57) **CLAIM**

The ornamental design for a squeeze bottle, as shown and described.

DESCRIPTION

FIG. 1 is a top perspective view of a squeeze bottle showing our new design;

FIG. 2 is a bottom perspective view of the squeeze bottle shown in FIG. 1;

FIG. 3 is a front view of the squeeze bottle shown in FIG. 1; FIG. 4 is a rear view of the squeeze bottle shown in FIG. 1; FIG. 5 is a right side view of the squeeze bottle shown in FIG. 1;

FIG. 6 is a left side view of the squeeze bottle shown in FIG. 1; FIG. 7 is a top view of the squeeze bottle shown in FIG. 1; and, FIG. 8 is a bottom view of the squeeze bottle shown in FIG. 1. The broken lines in the drawing depict portions of the squeeze bottle that form no part of the claimed design.
